PRECISION SCALE

Elmer D. Hurley, Memphis, Tenn.

Application September 13, 1943, Serial No. 502,125

2 Claims. (Cl. 33—103)

This invention relates to improvements in scales through which direct measurements, or halved divisions of such measurements, particularly adapted to effect the setting of the compass, as in drawing circles of certain diameter can be made.

The objects of the invention are:

To provide a scale through which extremely small variations in length may readily and accurately be measured; and

To further provide such a scale through which any given measurement may be halved, as in obtaining directly the radius of a circle of known diameter.

The means by which these and other objects are accomplished, and the method of their accomplishment, will readily be understood from the following specification upon reference to the accompanying drawing, in which:

Fig. 1 is a face view of the scale, a portion 20 only of the measuring blade being shown.

Fig. 2 is an end elevation of the head and the same portion of the blade; and

Fig. 3 a fragmentary section transversely to the head and the longer blade, taken as on the line III—III of Fig. 1, showing on an enlarged scale the way in which the blade is preferably slidably secured to the head.

Referring now to the drawing in which the various parts are indicated by numerals:

11 is a head, which may be of any desired length, and is marked with 100 equally spaced graduations 13 at right angles to its lower edge 12, every tenth, or as here shown, fifth graduation preferably being made heavier, in usual manner, and the graduations being marked from 0 to 100, in suitable manner.

The lower portion of this head is divided by longitudinal markings 17, 17A, 17B, which are spaced uniformly apart by increments, which have no necessary relation to the length increments, each increment being one tenth of the principal unit of length, which is to be used, this unit usually being one inch and hereinafter being so referred to, so that these lines, in such case, are uniformly one tenth of an inch apart. The upper of these lines 17A are marked 0 on the head, and being the base for length measurements. This lower portion of the head may be of any desired depth, as the six tenths here shown. From the intersection of the base line 17A, with the zero division 13A, the upper edge of the head diverges and increases the head depth by the exact amount of one inch at the one hundredth division 13B, successive intermediate divisions thus increasing in 55

length from left to right by increments, each a one hundredth of an inch and the respective lengths being marked along the lower edge of the head in hundredths.

5 Cooperating with this head is a shiftable blade 19 which extends truly at right angles from the head and is shiftable along the head to any desired position, this location in use being entirely governed by the measurement which it is desired to make. The blade 19 is preferably provided with a headed tenon 21 which closely, but slidably engages in a complementary groove extending throughout the length of the head. Preferably the blade is of slightly greater thickness than the head, in order that when the blade is positioned to make a measurement on a flat surface and is firmly held thereagainst the head may be readily shifted.

For convenience in cutting the groove, the head 20 may be split into two portions 11A, 11B and these portions, after the groove be cut, be secured together as by rivets 23, or otherwise as by gluing, welding or brazing, depending on the materials used.

25 The blade 19 has divisions 27 marked along its opposite edges, these divisions comprising main divisions spaced uniformly apart at the desired unit distance, here one inch, and marked by designating numbers 1, 2, 3, etc., depending on the length of blade used, and intermediate divisions, each one tenth of an inch.

The first of these main divisions 27A, marked "1" on the blade, is at such distance below the bottom edge of the head that it is exactly one inch from the naught longitudinal division 17A of the head, in the present instance this being four minor divisions or tenths, and additional main divisions are at equal intervals of one inch and marked 2, 3, etc., these comprising the main measurement divisions of the scale and being subdivided into tenths.

35 The blade is also marked with a longitudinal line 29, preferably along the center of the blade, which is transversely intersected at the main and five tenths, or half principal unit intervals, as at 31, and designated by the smaller numerals 2, 3, 4, 5, 6, 7, etc., these latter divisions being for obtaining radii of circles of given diameter. To 40 cooperate compass with the blade for this purpose, the upper portion of the head carries an additional longitudinal line 33, which extends from the intersection of the zero vertical and horizontal divisions 13A, 17A and diverges from the horizontal division 17A to an intersection with the 100 vertical division 13B, halving the edge

divergences at each intermediate division. It will here be particularly noted that the horizontal division line 17A of the head is the base for determining in connection with the diverging line 33 the radii of circles under one inch in diameter and the five tenths line 17B, the similar base for circle radii between one and two inches, the width six tenths of the lower portion of the head, and in fact, any other width chosen other than five tenths insuring that the measurement be not made from the joint line between the head and blade. For circles over two inches the centers 31 on the blade are used in connection with the line 33.

In using the device for establishing radii for circles less than one inch in diameter, the compass center is preferably set on the base line 17A of the head at its intersection with the hundredths line indicating the diameter of the circle, and the scribing point is set on the intersection of the same hundredths line with the line 33 and the setting obtained.

If the circle be over one and less than two inches, the measurements are still on the head only and the compass center is set on the base line 17B at its intersection with the desired hundredth line and the scribing point set on the intersection of the same hundredth line and the line 33 and the setting obtained.

If the circle be of greater diameter than two inches, the blade must also be used. In such case, the blade is shifted until the line 29 coincides with that one of the head division lines which indicates the number of one hundredths over and above even inches, the center of the compass is placed on that center 31 indicating even inches of diameter, and the scribing point on the intersection of the hundredths division line and the line 33, giving the desired radius for the circle.

As an example, it is assumed that it is desired to establish a compass setting to draw a circle 2.71 inches in diameter. The blade 19 has been shifted until the line 29 thereon coincides with the seventy-one hundredths mark on the head. If the center of the compass be now set at the center marking 31, corresponding to two inches, and the scribing point of the compass be moved to the point at which the seventy-one hundredths line crosses the line 33, the proper radius for a two and seventy-one hundredths circle has been set. Without shift of the blade, additional compass settings may similarly be made for any other number of inches, plus seventy-one hundredths, but for each change in hundredths, blade shift must be made.

In using the device for making measurements, one or the other of the edges of the blade of the scale is laid along the line to be measured with an even inch division mark at one end of the measurement to be made, the blade is held firmly against the surface on which the to be measured line exists and the head is shifted forward or backward, as the case may be, until the upper edge of the head is exactly on the opposite end of the line, the length of the line comprising the

number of inches shown on the blade and the number of hundredths shown on the head.

In Fig. 2, if the measurement being made is of a line extending from the three inch mark and along the left hand edge of the blade and the head has been shifted so that its upper edge is at the opposite end of the line, the length shown is three inches and six hundred and forty-five thousandths, whereas, if the right hand edge of the blade is along the line to be measured and the head has been properly shifted, the measurement from the three inch mark indicates a length of three inches and seven hundred and seventy-five thousandths.

It will be understood that the hundredth divisions on the head may be further subdivided into thousandths if desired.

I claim:

1. A precision scale comprising an elongated head, and an elongated blade, slidably secured at right angles to one edge of said head for manual shifting therealong, said head being longitudinally divided into one hundred equal increments indicated by markings at right angles to its said lower edge and numbered at suitable intervals, and by a primary base line extending from end to end thereof parallel to said edge, the opposite edge of said head diverging from the intersection of the zero of said markings and said base line to the one hundredth said marking in an amount of one unit of length on said blade; said head having also a secondary longitudinal base line, bisecting the angle of divergence of said edge from said primary base line, said blade having at least one of its edges divided into and marked at equal unit intervals of length, the first said marking being at exactly one unit interval from said head base line, and a base line extending longitudinally thereof parallel with said edge, and divided into, and marked at one-half unit intervals, the zero of said one-half unit intervals and marking being said head base line.

2. A precision scale comprising an elongated thin flat head, of substantially uniform thickness throughout, and an elongated thin flat blade of substantially equal thickness, disposed at right angles to one edge of said head and in end abutting relation thereto, with the upper surfaces of said head and blade lying in substantially the same plane, said blade being slidably secured for manual shifting therealong; said head longitudinally being divided into one hundred equal increments indicated by markings at right angles to its said lower edge and numbered from 0 to 100 at intervals, and by a base line extending from end to end thereof parallel to said edge, the opposite edge of said head diverging from the intersection of the zero of said markings and said base line to the one hundredth said marking in an amount of ten said increments; said blade having at least one of its edges divided into and marked at equal unit intervals of ten said increments, the first said marking being at exactly one unit interval from said head base line.
